F. J. MILLER

RECIPROCATING PUMP

Filed April 6, 1923

FRANK J. MILLER, INVENTOR

Jesse R. Stone
HIS ATTORNEY

UNITED STATES PATENT OFFICE.

FRANK J. MILLER, OF WICHITA FALLS, TEXAS, ASSIGNOR, BY MESNE ASSIGNMENTS, TO
L. E. TROUT, OF OKLAHOMA CITY, OKLAHOMA.

RECIPROCATING PUMP.

Application filed April 6, 1923. Serial No. 630,222.

To all whom it may concern:

Be it known that I, FRANK J. MILLER, a citizen of the United States, residing at Wichita Falls, Wichita County, Texas, have invented a certain new and useful Improvement in Reciprocating Pumps, of which the following is a full, clear, and exact description, such as will enable others skilled in the art to which it appertains to make and use the same.

My invention relates to pumps such as are employed in pumping deep wells for oil or water.

The object of my invention is to provide a reciprocating pump of the deep well type wherein the ordinary working barrel usually employed may be dispensed with.

Another object is to provide a plunger which will telescope over the standing valve 20 in the bottom of the well in such manner as to provide sufficient suction without the use of the ordinary packing means.

Another object is to provide a plunger of the type described whereby the outer telescoping portion thereof may be detachably secured to the body of the plunger in such manner that the plunger itself may be removed from the well without the necessity of also removing the telescoping sleeve.

Referring to the drawing herewith, I have shown a central longitudinal section through a pump tubing and standing valve using my improved plunger employed in connection therewith.

In carrying out my invention I preferably provide a pump barrel 1 wherein the plunger may reciprocate, which pump barrel is of larger diameter than the main tubing 2 extending from the surface down to

the bottom of the well. The tubing 2 is connected to the larger pump barrel 1 by means of a swedged coupling or nipple 3, the tubing and pump barrel both being threaded externally for attachment within the said coupling.

At the lower end of the pump barrel 1 is a special coupling 4 of the usual construction by means of which the pump barrel is connected to the strainer or perforated pipe 5 below the standing valve. The central portion of the coupling is of comparatively small internal diameter and provides a recess tapered at 6 to provide a seat for a standing valve 7 which may be wedged downwardly into said seat for operation in

the usual manner. The upper end of the standing valve 7 is provided with a valve seat 9 and ball valve 10 secured in place by a cage 11. The upper end of the cage is provided with a threaded socket 12 whereby a setting tool may be employed to force the valve and its housing downwardly into the coupling.

The upper end of the valve chamber within the coupling 4 is enlarged and threaded at 13 to receive the lower end of an upright tube 14. This tube extends upwardly within the pump barrel for somewhat over half the length of the said barrel. It is provided with smooth outer and inner surfaces to provide a close sliding contact with the plunger which is adapted to telescope over said tube.

The plunger used in connection with my pump has a head 16, threaded on its outer surface for connection to a valve cage 17, said cage being formed to clamp upon the upper end of the head 16 a valve seat 18 to accommodate a ball valve 19. The upper end of the said cage is connected to a sucker rod 20 by means of which the plunger may be reciprocated. The lower end of the plunger is reduced in diameter and has thereon a series of cups 21 spaced apart by means of spacing collars 22. These packing cups are of flexible material and are directed outwardly in the usual manner. The lower end of the head of the plunger is threaded on its outer surface for attachment to a downwardly extending sleeve 23. This sleeve is of sufficient external diameter to fit tightly but slidably within the foot valve tube 14 so as to maintain a suction effect therewith.

Outside the body of the plunger is a second telescoping sleeve, said outer sleeve being retained frictionally upon the head of the plunger by contact with the cups 21 previously described. The upper end of the sleeve is connected to a nipple 24 which is of large internal diameter adjacent the upper end, to receive the head of the plunger. The inner walls are beveled inwardly at 25 and thickened to make a close fit with the packing cups 21 upon the plunger. The lower end of the nipple 24 is reduced in diameter and threaded at 26 for attachment to the telescoping sleeve 27 which fits slidably over the outer surface of the foot valve tube 14. The inner sleeve 23 upon the plunger

is perforated at 28 to allow escape of fluid from within the chamber 29 formed between the two telescoping sleeves upon the plunger during the operation of the pump.

5 In installing this device the pump barrel 1 and foot valve and coupling, together with the perforated pipe, are secured together with the upright tube 14 thereon in the manner shown. The nipple 24, connected 10 with the plunger is then placed within the pump barrel, telescoping down over the tube 14. The tubing then is connected to the pump barrel by means of the coupling 3 and the device is introduced into the well 15 ready for operation. The plunger is of the proper external diameter at its largest point to fit slidably within the tubing and is introduced downwardly into the pump barrel. The lower end comprising the tube 23 and 20 the packing cups 21 will fit closely within the lower portion of the nipple 24 and will make a tight wedging fit therewith. When the lower end of the valve cage 17 comes in contact with the beveled portion 25 of the 25 nipple 24 the plunger will stop and the device will be ready for reciprocation. The tight fit between the plunger and the outer sleeve connected with the plunger will be sufficient to cause the two to reciprocate together in operation, and it will be noted that 30 on the upward stroke of the plunger the tight fit between the inner and outer sleeves of the plunger telescoping over the standing valve tube will be sufficient to preserve the usual suction. This is especially true 35 where oil fills the space between the sliding tubes. The oil will be drawn upwardly past the standing valve, filling the inner chamber within the tube 14. On the downward stroke this fluid will be forced upwardly 40 past the valve 19, into the tubing, toward the surface. The small opening 28 will prevent the formation of a vacuum in the chamber 29 and assist in the easy operation 45 of the plunger.

When it is desired to withdraw the plunger, due to any cause, the sucker rod will be pulled upwardly with some force, bringing the upper end of the nipple 24 in 50 contact with the shoulder provided at 30 on the lower face of the coupling 3. This will jar the outer nipple and sleeve loose from the body of the plunger, allowing the said plunger to be withdrawn, leaving the outer barrel in the well. When the plunger has 55 been repaired either as to the valve or to the cups 21, it may be again introduced into the well, and will be wedged into tight contact with the outer sleeve in the manner previously described.

60 A pump of this type will have many obvious advantages in that no working barrel will be needed, and a suction means is provided wherein no packing cups of the ordinary type are necessary for maintaining the

contact between the standing valve and the plunger. Sand will not readily work in between the telescoping parts and little wear will occur under ordinary conditions of operation, making it possible to operate the 70 pump successfully for long periods of time.

Having thus described my invention, what I claim as new and desire to protect by Letters Patent is:

1. In a pump, a tubing, a pump barrel 75 thereon of larger diameter than said tubing, a standing valve secured to the lower end of said pump barrel, a stationary tube projecting upwardly from said standing valve, a plunger, a tube on said plunger telescoping within said stationary tube and a tube of larger diameter secured frictionally to said plunger and adapted to telescope over said stationary tube.

2. In a pump, a tubing, a pump barrel 80 thereon of larger diameter than said tubing, a standing valve secured to the lower end of said pump barrel, a stationary tube projecting upwardly from said standing valve, a plunger adapted to pass through said tubing, an outer tube in said pump barrel, said outer tube being of smaller internal diameter than said tubing, said plunger adapted to be wedged frictionally within said outer tube and said outer tube being adapted to telescope closely over said stationary tube.

3. In a pump, a tubing, a pump barrel 85 thereon of larger diameter than said tubing, a foot valve on said tubing, a stationary tube surrounding said standing valve and 100 projecting upwardly therefrom, a plunger adapted to slidably fit said tubing, an outer plunger tube into which said plunger is formed to fit, cups on said plunger maintaining a tight frictional hold on said outer tube, 105 and an inner tube on said plunger adapted to telescope within said stationary tube.

4. In a pump, a tubing, a pump barrel 110 therein of larger diameter than said tubing, a standing valve, a stationary tube projecting upwardly from said standing valve, a plunger, an outer tube frictionally fitting about said plunger and to telescope over 115 said stationary tube, and means on said tubing to retain said outer tube within the pump barrel.

5. In a pump, a plunger, a head, a reduced extension at the lower end thereof, packing cups thereon, a tube secured to the lower end of said extension, an outer tube into 120 which said plunger and packing cups fit tightly whereby said outer tube may reciprocate with said plunger, and a stationary tube on which the tubes on said plunger may slidably fit.

6. In a pump a pump barrel, a plunger, a head, packing cups below said head, a tube below said cups, an outer tube frictionally engaged over said cups, a stationary tube in the lower end of said pump barrel, said tube 125

formed to fit slidably between the tubes on said plunger and a communicating passage from above said stationary tube to the inside of the plunger.

5 7. In a pump, a pump barrel, a plunger out of contact with said barrel, a stationary tube in the lower end of said barrel, inner and outer tubes on said plunger fitting slid-

ably on said stationary tube, means to maintain a fluid-tight frictional fit between said 10 outer tube and said plunger, and means on said pump barrel to prevent withdrawal of said outer tube with said plunger.

In testimony whereof, I hereunto affix my signature, this 29th day of March A.D. 1923.

FRANK J. MILLER.
